UNITED STATES PATENT OFFICE.

ABBOT AUGUSTUS LOW, OF NEW YORK, N. Y.

DESIGN FOR A BOTTLE.

SPECIFICATION forming part of Design No. 31,235, dated July 18, 1899.

Application filed June 17, 1899. Serial No. 721,000. Term of patent 14 years.

To all whom it may concern:

Be it known that I, ABBOT AUGUSTUS LOW, a citizen of the United States, residing in the city of New York, borough of Brooklyn, in the county of Kings and State of New York, have invented a new and original Design for Bottles, of which the following is a specification, reference being had to the accompanying drawings, forming a part thereof.

10 Figure 1 is a side elevation of my new design; Fig. 2, a vertical section upon plane of line 2 2, Fig. 3. Fig. 3 is a plan thereof.

As shown in the drawings, the distinguishing feature of my design consists in a square-shaped bottle B, merging into a curved top a, having a comparatively large cylindrical neck

15 N, with external spiral bead S, said cylindrical neck approximating in diameter the width of a side of the square body A and the total height of the body B and its cylindrical neck N being less than the width of a side of the body.

Having now described my invention, what I claim as new, and desire to secure by Letters Patent, is—

20 The design for a bottle, as herein shown and described.

25 ABBOT AUGUSTUS LOW.
